UNITED STATES PATENT OFFICE.

FRANK B. WILDMAN, OF NORRISTOWN, PENNSYLVANIA.

CIRCULAR-KNITTING MACHINE.

1,081,179.

Specification of Letters Patent.

Patented Dec. 9, 1913.

Application filed October 7, 1912. Serial No. 724,376.

To all whom it may concern:

Be it known that I, FRANK B. WILDMAN, a citizen of the United States, residing at Norristown, Pennsylvania, have invented certain new and useful Improvements in Circular-Knitting Machines, of which the following is a specification.

It is the object of the invention to provide a circular knitting machine of small diameter for making small diameter tubular fabric, and the invention concerns particularly the construction of the needle cylinder and the cam cylinder in their relation one to the other whereby the needle row at the point of knitting may be of very small diameter, while at the same time the cam box will be of sufficient diameter to provide a satisfactory cam race to operate the needles.

20 The invention consists in the features of construction and arrangement and combination of parts hereinafter described and particularly defined by the appended claims.

The accompanying drawing represents a central vertical sectional view through a machine embodying the invention.

In this drawing, 1 represents the needle cylinder, which is of tapered form, and which extends a considerable distance above the cam box 2, which carries the cam pieces forming the cam race 3. The tapered cylinder is grooved to receive the needles, as in ordinary practice, and the butts of these needles, as in ordinary practice, enter the cam race 3. The cams are arranged in cylindrical form, as shown, but owing to the slight taper of the needle cylinder the needles, in their up and down movement, traverse a path only slightly inclined to the 40 interior of the cam cylinder so that in their up and down movement the butts of the needles maintain engagement with the cam race. In order to get the needle cylinder at the knitting point of the required small diameter, the said cylinder, as above stated, is extended a considerable distance above the cam box. By arranging the cams in cylindrical form and by employing a cylin-

der of elongated tapered form, the diameter of the parts at the needle cams may be 50 considerable as compared with the diameter of the needle cylinder at the knitting point, and the room thus provided will enable a satisfactory cam race to be formed, as shown, and the needles will project into the 55 cam race a sufficient distance for proper operation and control throughout their extent of movement in a vertical plane. In order to hold the needles into the grooves of the cylinder, a collar is provided at 4, the 60 interior of this collar being tapered to fit the taper of the cylinder.

It will be observed that the needles traverse a path out of parallel with the plane of the cam surface, and as a result of this 65 the needles at their work ends lie in a circle of very small diameter, while at their butts they lie in a circle of much larger diameter, making it possible to employ a cam cylinder of a considerable size.

70 I claim as my invention:—

1. A knitting machine consisting of an elongated needle bed of conical form, with its taper upward and a cam box surrounding the lower larger diameter portion of the 75 taper cylinder, said cam box having its cams arranged in plain cylindrical form, the needles traversing a path out of parallel with the cam surface, and inclining toward the center of the plain cylinder, substantially 80 as described.

2. A knitting machine consisting of an elongated needle bed of conical form with its taper upward, a cam box surrounding the lower larger diameter portion of the 85 conical needle bed, and a loose ring surrounding the conical needle bed to hold the needles in the grooves thereof, substantially as described.

In testimony whereof, I affix my signature in presence of two witnesses.

FRANK B. WILDMAN.
